(57) **CLAIM**

The ornamental design for a patio rocking chair, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a patio rocking chair, showing my design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof; and,

FIG. 7 is a top plan view thereof.

Colors shown in FIGS. 1 to 7 are for illustration purposes only, do not form any part of the claimed patio rocking chair.
